TOY MUSICAL INSTRUMENT

William Kratt, Union, and Emil J. Ens, Newark,
N. J., assignors to Wm. Kratt Co., a corpora-
tion of New Jersey

Application November 18, 1952, Serial No. 22,351

Term of patent 14 years

(Cl. D34—15)

To all whom it may concern:

Be it known, that William Kratt and Emil J. Ens, respectively, a citizen of the United States, residing at Union, in the county of Union and State of New Jersey and a citizen of the United States, residing at Newark, in the county of Essex and State of New Jersey, have invented a new, original, and ornamental Design for a Toy Musical Instrument, of which the following is a specification, reference being had to the accompanying drawing, forming part thereof.

In the drawing

Fig. 1 is a top plan view of a toy musical instrument, showing our new design;

Fig. 2 is a front elevational view thereof;

Fig. 3 is an end view thereof; and

Fig. 4 is a fragmentary bottom plan view

thereof, a portion of the mouthpiece being broken away for convenience of illustration.

We claim:

The ornamental design for a toy musical instrument, as shown and described.

WILLIAM KRATT.
EMIL J. ENS.
